United States Patent Office.

NICHOLAS S. VEDDER, OF TROY, AND TOBIAS S. HEISTER, OF LANSINGBURG, NEW YORK, ASSIGNEES TO NICHOLAS S. VEDDER.

Design No. 3,865, dated February 22, 1870.

DESIGN FOR A STOVE-PLATE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented and produced a new and original Design for Plates or Castings of Cooking-Stoves, of which the following is a specification, reference being had to the accompanying photographic illustration.

Our design for a door or doors, or a plate or plates of a cooking-stove consists of the compound central ornament *d* or *d'*, on a plane surface, *e*, surrounded by the ornamental frame-like border *f* or *f'*, the same being shaped and arranged so as to appear as shown by

the aforesaid photograph, in which our design for the foot *g* is represented.

What we claim as our invention or production, and desire to secure by Letters Patent is—

The design for a foot and a door or doors, or a plate or plates of a cooking-stove, as herein specified and represented by the accompanying photographic illustration.

NICHOLAS S. VEDDER.
TOBIAS S. HEISTER.
